Des. 242,518
Patented Nov. 30, 1976

242,518

ELECTRIC HEATING ELEMENT

Frank T. Walton, 656 13th St.,
Oakmont, Pa. 15139

Filed Aug. 11, 1975, Ser. No. 603,320

Term of patent 14 years

Int. Cl. D7—05

U.S. Cl. D7—136

FIG. 1.

FIG. 2.

FIG. 3.

FIG. 4.

FIG. 1 is a top plan view of an electric heating element, showing my new design;

FIG. 2 is a side view elevational thereof; and

FIGS. 3 and 4 are transverse sectional views corresponding to the lines 3—3 of FIG. 1 and line 4—4 of FIG. 2, respectively.

I claim:

The ornamental design for an electric heating element, substantially as shown.
